UNITED STATES PATENT OFFICE.

THEODORE A. HOLMBERG, OF CLEVELAND, OHIO.

GAS-BURNER.

1,221,535.

Specification of Letters Patent.

Patented Apr. 3, 1917.

Application filed October 12, 1916. Serial No. 125,153.

To all whom it may concern:

Be it known that I, THEODORE A. HOLMBERG, a citizen of the United States, residing at Cleveland, in the county of Cuyahoga and State of Ohio, have invented certain new and useful Improvements in Gas-Burners, of which the following is a specification.

My invention relates to improvements in gas burners, and more particularly to that 10 class or type known as "inclosed flame gas burners," the present embodiment of this invention being particularly designed and adapted for use in large ovens for providing a proper circulation of heated air for baking 15 and drying various commercial articles, as in enameling, japanning, baking, drying and the like.

The primary object of the invention is to provide a generally improved burner of this 20 class which will be exceedingly simple, cheap, and efficient in use, as well as one in which the parts are so constructed and arranged relative to each other as to result in a more perfect combustion within the generator, 25 proved means being provided for supplying air under pressure within the generator, and thereby forcing highly heated air from the latter into the oven under pressure giving an even and rapid circulation for driving 30 off dampness and fumes from the oven and articles being baked or dried.

A further object is the provision of an improved generator or combustion chamber in which a more complete combustion and a 35 more rapid circulation of heated air is provided, as well as one in which the various burner and air distributing pipes and nozzles will be rendered more durable and efficient in service.

With the above mentioned and other ends 40 in view, the invention consists in the novel construction, arrangement, and combination of parts, hereinafter described, illustrated in one of its embodiments in the accompanying 45 drawings, and particularly pointed out in the appended claims.

Referring to the drawings, forming a part of this specification, Figure 1, is an end view of the front or air and gas receiving 50 end of a burner constructed in accordance with this invention.

Fig. 2, a cross sectional view of the same.

Fig. 3, a top plan view of the same, a portion of the generator or flame inclosing casing 55 being broken away for the purpose of clearer illustration of parts.

Fig. 4, a side elevation of the same, the gas burner pipes being removed.

Similar numerals of reference designate like parts throughout all the figures of the 60 drawings.

The improved gas burner comprises a generator or flame inclosing casing 1, which is preferably made up of a series of sections or units terminating at their ends in flanges 65 1^a, the latter adapted to be connected in any suitable and convenient manner to form a generator of suitable length to conform to the dimensions of the oven in which it is to be used.

The sections or units of the generator casing are preferably provided at their ends with legs or supports 1^b, to rest upon the floor of the oven, suitable air circulating passages or recesses 1^c, being provided between 70 the legs or supports and on each side leading to the base portion of the generator casing.

The end sections or units are preferably provided with cylindrical heads 1^d, the head 75 1^d, at the front, being adapted to be intersected by suitable air and gas conduit pipes 2, and 3, respectively, leading to the air distribution and gas burner pipes within the casing 1, hereinafter described. The air and gas conduit pipes 2, and 3, may be provided 80 with suitable valves for regulating the flow of air and gas, but such valves forming no part of this invention need not be shown or described.

As a means of heating the air as well as 90 providing for proper combustion within the generator casing or combustion chamber provided by the latter suitable longitudinally extending gas burners 4, are provided, said burners 4, in the present instance, being 95 in the form of longitudinally extending burner pipes suitably spaced apart and communicating with the gas conduit pipe 3, at the front.

As a means of properly distributing the 100 hot air and products of combustion from the generator or flame inclosing casing 1, the latter is provided with a series of heat distributing laterals or pipes 5, suitably spaced and located, said pipes terminating at their 105 ends in upwardly extending portions 5^a, provided with suitable air distributing caps 5^b, the latter being spaced above the outlet portions 5^a, to provide outlet portions 5^c, intermediate the caps 5^b, and the upwardly 110 extending portions 5^a.

As a means of further promoting combus-

2
tion and accelerating the passage of hot air and the products of combustion from the burners 4, and through the heat distributing laterals 5, an air conduit pipe 6, is mounted 5 within the generator casing 1, above the burners 4, and is provided with a series of air distributing laterals 6^a, in alinement with and adapted to discharge air through the heat distributing laterals 5, above referred to.

10 The main air conduit pipe 2, at the front is also provided along its top and substantially midway between the air distributing pipes 6^a, with vertically extending air distributing pipes 6^b, adapted to discharge air within the top or dome portion of the generator or flame inclosing casing 1, as shown most clearly in Fig. 2 of the drawings.

15 The air conduit pipe 6, may be supported at suitable intervals throughout its length 20 with cross bars 1^c, within the casing 1, (see Fig. 2,) and it will be observed that by reason of the location of the pipe 6, and air distributing laterals 6^a, above the burner pipes 25 4, the gas flames issuing from the latter will act to heat the pipe 6, and laterals 6^a, and the air issuing from the same, the air issuing from the air distributing laterals 6^a, and into and through the heat distributing laterals 5, constantly carrying off and distributing 30 the heated air and the products of combustion arising from and over the burners 4, and this circulation of air also adds longer life to the burner pipes 4, for obvious reasons.

35 From the foregoing description, taken in connection with the accompanying drawings, the operation and advantages of my invention will be readily understood.

Having thus described one of the embodiments of my invention, what I claim and desire to secure by Letters Patent, is,—

40 1. In a gas burner, a generator casing made up of a plurality of sections open at their bottoms and provided with heat distributing lateral pipes terminating in upwardly extending portions covered with spaced air distributing caps.

45 2. In a gas burner, a generator casing open at its bottom and provided at its sides with heat distributing laterals, a pipe provided 50 with air distributing laterals in alinement with said heat distributing laterals, and gas burners in said casing above said open bottom of said casing and below said pipe and air distributing laterals.

55 3. In a gas burner, a generator casing provided with heat distributing laterals, an air conduit pipe therein provided with air distributing laterals in alinement with and leading 60 to said heat distributing laterals, and gas burner pipes in said generator casing

below said air conduit pipe and heat and air distributing laterals.

4. In a gas burner, a flame inclosing generator casing provided with lateral heat distributing pipes, a central air conduit therein provided with laterals in alinement with and adapted to discharge air through said lateral heat distributing pipes, and gas burners in said casing below said air conduit and laterals whereby the latter are heated and the products of combustion are carried through said heat distributing pipe with the air discharged therein by said air discharging laterals.

75 5. In a gas burner, an elongated flame inclosing generator casing open at its bottom and provided with supporting legs, a series of lateral air distributing pipes extending from the sides of said casing, and an air conduit pipe in said casing provided with air distributing laterals in alinement with said lateral air distributing pipes, and upwardly extending air distributing pipes intermediate the latter and below the dome 80 portion of said casing.

6. In a gas burner, an elongated generator casing made up of connected sections provided with air inlet passages in their bottom portions and heat distributing lateral pipes 90 at their sides, gas burner pipes above said air inlet passages, and an air conduit pipe above said burner pipes and provided with air distributing laterals adapted to discharge air through said heat distributing 95 lateral pipes whereby the heat and products of combustion arising from said burner pipes are carried through said lateral pipes with the air discharged therein by said air discharging laterals.

100 7. In a gas burner, an elongated flame inclosing generator casing provided with an open bottom and air inlet passages leading thereto, heat distributing lateral pipes at the sides of said casing, an air conduit in 105 said casing provided with air distributing laterals in alinement with and adapted to discharge air through said heat distributing lateral pipes, and gas burner pipes in said casing above said air inlet passages 110 and below said air conduit and air distributing laterals whereby the latter are heated and the products of combustion are accelerated in their passage through said heat distributing lateral pipes.

115 In testimony whereof I have affixed my signature in the presence of two witnesses.

THEODORE A. HOLMBERG.
